DRAFT ARM NOZZLE

Mortimer J. Brown, Niagara Falls, N. Y.

Application February 28, 1939, Serial No. 258,892

6 Claims. (Cl. 225—24)

This invention relates to apparatus for discharging supersaturated aqueous solutions of carbon dioxide, such as carbonated beverages, beer, etc., without excessive loss of dissolved gas, and 5 has for its object to provide a new and improved apparatus for this purpose.

In my Patent #1,956,143 of April 24, 1934, I disclosed a new method for discharging carbonated water from pressure containers. The 10 most important feature of said method was the use of friction between a thin film of rapidly moving water, and a smooth braking surface, for the purpose of reducing the velocity of the liquid, without violence.

As carbonated water is used at soda fountains, in the home, etc., and drawn into drinking glasses for use, the rate of withdrawal into glasses is of the order of about one ounce per second. Also, the pressure used in the pressure containers is 20 usually about 125 pounds per square inch. Since carbonated water loses its gas of supersaturation when handled violently, it is highly desirable to deliver the water into the glass in a slow stream. However, it is physically impossible to draw water 25 from a pressure container at 125 pounds pressure, and at a rate of one ounce per second, without developing a very high velocity of the liquid at a point immediately on the low-pressure side of the controlling orifice.

According to the invention disclosed in Patent #1,956,143, I pass water through an orifice which has one very small dimension so as to deliver a rapidly moving film of water. Furthermore, that film is discharged in contact with a smooth braking surface which functions also as a collector to gather together all of the water, after its velocity is reduced, for delivery at one point. The apparatus disclosed in my above-mentioned patent included a precise adjustment of the orifice, which 35 adjustment was fixed and invariable until it was changed by the operator. In practical use, the necessity of making such adjustment was found to be undesirable, and it was also found that fine solid particles had a tendency to clog the orifice, 40 the clearance of which was only a few thousandths of an inch.

My present invention uses the basic principle of Patent #1,956,143. The orifice, however, is not fixed, but is automatically variable, entirely closed 50 when water is not passing through it, and never open more than is necessary to carry the water that is passing through it. I accomplish this by building the orifice as a pop-off valve, with the movable face of the orifice of a material sufficiently elastic and resilient to favor an even dis-

tribution of the water along the entire delivery opening of the orifice.

When the apparatus of my prior patent is used, with or without the present new improvement, the device for permitting the water to flow or prevent it from flowing, is up in the head of the draft arm. Any good mechanism may be used. With an accurately adjusted orifice as disclosed in the prior patent, the full pressure drop was taken at the fixed orifice. With the present improvement hereinafter disclosed, a part of the pressure drop is taken up in the head at the on-and-off control, and a part is taken at the pop-off orifice which delivers the thin film of water to the braking surface.

While theoretically it is better to take all of the drop of pressure at the orifice which delivers the thin film of water to the braking surface, practically there is little difference in this respect between the older and the improved equipment, 20 because of the relative temperatures that prevail in the carbonator where the carbonated water is made, and in the water as it passes through the draft arm. Because of the final refrigeration just before it goes into the draft arm, the water 25 is not completely saturated when it passes through the on-and-off control. The tendency for the gas to leave the water is not substantial until the pressure falls to such a point that the water is supersaturated. As a matter of fact, 30 the draft arms using the principle of Patent #1,956,143, and the improvement I am here disclosing, give strikingly better results than any other draft arms I know about that do not use my main principle.

The various features and advantages of the present invention will be described in connection with the accompanying drawing, wherein:

Fig. 1 is a longitudinal sectional view of a standard soda fountain faucet arm with my improved draft arm nozzle applied thereto; and

Fig. 2 is a top plan view of said nozzle.

In the drawing I show a standard soda fountain faucet arm 1 leading to a rotary valve 2 operated by handle 3 and adapted to be connected either 45 to port 4 or port 5. The port 4 leads to passage 6 in the valve body while port 5 leads to a passage 7 as shown in Fig. 1.

The nozzle of my invention comprises a body portion 8, preferably of metal, having a threaded 50 neck 9 which is screwed into the head of the draft arm as shown in Fig. 1. When thus screwed in place, the passage 6 of the valve body communicates with a central passage 10 in the stem of my attachment for discharging the usual 55

needle stream through orifice 12, while passage 7 of the valve body communicates with the annular passage 13 in the body portion 8 of my attachment. Since this invention does not pertain to the needle stream, it need not be discussed here.

When water is delivered to the annular passage 13, it passes downward through the passages 14 to the annular orifice chamber 15. On the under side of the body is the rubber disc 16, and there 10 is a small annular opening from chamber 15 to the face of the rubber disc 16. Below the rubber disc is a washer 17, below that a compression spring 18, and below that a nut 19. The combination 15 of nut, spring and washer makes it possible to exert a pressure on the under side of the rubber disc 16 so as to force it up against the under side of the body 8. The under side of the body 8 is concave, turning downwardly and joining flush with the inside walls of the conical collector 20, thus constituting the smooth polished braking 20 surface 21 the central portion of which surrounds the opening in chamber 15 and forms a seat for the disc 16.

In operation, the pressure of the spring 18 on 25 the disc 16 is adjusted at a point low enough so that the water pressure from above can force the resilient disc away from the braking surface, so that it functions as a pop-off valve. Whether the flow of water be large or small, the disc 16 moves 30 only sufficiently to let the water escape. The water escapes uniformly in all directions, in a thin film at high velocity, and in contact with the braking surface.

In accordance with the principle as disclosed in 35 my Patent #1,956,143, the braking surface 21 extends in the direction of discharge and holds the film in contact therewith until its velocity is substantially reduced. The water loses its velocity rapidly, without collisions of any kind, and is simultaneously collected into a single stream of 40 moderate velocity as it escapes from the final outlet 22.

For the disc 16, I prefer to use a vulcanized 45 gum rubber. The center hole of the disc is made quite small so that after being stretched around the stem, it is tight enough so as not to leak at that point. The washer 17 is made so that it exerts its pressure at the periphery of the disc. The same effect can be had by molding the disc of 50 such dimensions that it is thicker at the periphery, and then using a flat washer.

It will be seen that my invention resides in adapting the principle of the pop-off valve to equipment wherein the principle of my Patent 55 #1,956,143 is embodied. The result obtained is an automatic adjustment of the orifice to any rate of flow as it may be determined by the on-and-off control mechanism in the complete assembly. The invention can be applied to any sort of control valve for the use of carbonated water.

The invention claimed is:

1. In a carbonated liquid discharge device, the combination with means for supplying liquid under pressure, an orifice chamber connected

thereto, and a braking surface outwardly of said orifice chamber extending in the direction of discharge, of a valve normally closing said orifice chamber and actuated by the pressure of the liquid in said chamber to discharge said liquid in contact with said braking surface.

2. In a carbonated liquid discharge device, the combination with means for supplying liquid under pressure, an annular orifice chamber connected thereto, and a braking surface outwardly 10 of said orifice chamber extending in the direction of discharge, of a pop-off valve including a resilient disc normally closing said orifice chamber and actuated by the pressure of the liquid on said disc to discharge said liquid in contact with said 15 braking surface.

3. In a carbonated liquid discharge device, the combination with means for supplying liquid under pressure, an annular orifice chamber connected thereto, and a concave braking surface 20 outwardly of said orifice chamber extending in the direction of discharge, of a pop-off valve including a resilient disc normally seated on said braking surface to close said orifice chamber and tensioned to open uniformly under pressure of 25 said liquid to provide an even distribution of liquid over said braking surface.

4. In a carbonated liquid discharge device, the combination with means for supplying liquid under pressure, an annular orifice chamber connected thereto, and a concave braking surface 30 outwardly of said orifice chamber extending in the direction of discharge, of a pop-off valve including a resilient disc normally seated on said braking surface to close said orifice and a spring 35 exerting tension about the periphery of said disc to insure uniform opening of said valve and an even distribution of liquid in contact with said braking surface.

5. In a carbonated liquid discharge device, the 40 combination with means for supplying liquid under pressure, an annular orifice chamber connected thereto, and a concave braking surface outwardly of said orifice chamber extending in the direction of discharge, of a pop-off valve 45 including a valve stem disposed centrally of said orifice chamber, a resilient disc supported by said stem, and a compression spring surrounding said stem and acting on said disc to close said orifice chamber, said spring exerting tension about the 50 periphery of said disc and being actuated by the pressure of the liquid in said orifice chamber to discharge said liquid evenly in contact with said braking surface.

6. In a carbonated liquid discharge device, the 55 combination with means for supplying liquid under pressure, an orifice chamber connected thereto, and a braking surface extending from the low-pressure side of the orifice, of a pop-off valve tensioned to open under the pressure of the 60 liquid and positioned to deliver the liquid in contact with the braking surface and in a direction substantially parallel to the braking surface.

MORTIMER J. BROWN.
